COMBINATION LOCK

Hernfrid Evald Berggren, Stockholm, Sweden

Application December 10, 1940, Serial No. 369,453
In Sweden November 21, 1938

22 Claims. (Cl. 70—305)

The present invention refers to locking means with an operating member movable only by oscillation for the adjustment of the tumblers and provided for this purpose with carrier members, for instance in the form of teeth, pins or the like, said members being adapted to be set or shifted by the oscillatory movement in relation to the operating member, and being movable only in planes at right angles to the axis of oscillation. The arrangement according to the invention is principally distinguished by the feature that said operating member is provided with such carrier members also for moving the tumblers into their initial positions and for the operation of the bolt of the lock. Hereby it will be found possible to operate all of the members of the lock by means of a single operating member.

Locks having operating members provided with the means referred to by the present invention are particularly well adapted through this construction for being operated by means of a finger dial, for instance of the type disclosed in my Swedish Patent No. 90,026. The arrangement is believed to be advantageously serviceable in safe-locks as well as in ordinary door-locks, such as hall locks or automobile locks. As the arrangement is also comparatively simple, the manufacturing costs of these locks are believed to become rather low. Moreover, the locks in question become very much easier to manipulate than the locks of earlier constructions, without their safety in operation being reduced in the least.

The invention will be described more closely in the following with reference to the accompanying drawings which illustrate three forms of embodiment of the invention, further features characteristic of the invention, and the advantages involved thereby, being then also set forth.

In the drawings, Figs. 1 to 7 show a first embodiment of the contrivance as applied to a safe-lock, the oscillating operating member of which is provided with carrier teeth secured to an eccentrically mounted shifting or setting shaft.

Fig. 1 is a vertical section of said lock on line I—I in Fig. 2;

Fig. 2 shows a horizontal section of the same lock on line II—II in Fig. 1;

Fig. 3 is a vertical section of the lock on line III—III in Fig. 2;

Figs. 4 and 5 show the two constituent parts from which a tumbler is composed;

Fig. 6 shows a spacing and bearing washer for the tumblers;

Fig. 7 is a view to a somewhat smaller scale 55

than that of the other figures, of a finger dial for oscillating the operating member.

Figs. 8 to 11 show a second embodiment in which the carrier teeth of the operating member are arranged to be shifted by radial displacement under the influence of eccentrically arranged pins on a centrally mounted shifting or setting shaft.

Fig. 8 is a horizontal section through the central shaft of the operating member on line VIII—VIII in Fig. 9;

Fig. 9 is a vertical section on the line IX—IX in Fig. 8;

Fig. 10 is a vertical section on line X—X in Fig. 8;

Fig. 11 is a side view of a ratchet wheel and pawls for turning the shifting or setting shaft;

Figs. 12 to 18 show a third embodiment, the operating oscillating member of which is provided with carrier teeth secured to a shifting or setting roller eccentrically mounted outside the tumblers;

Fig. 12 is a sectional front view with a detail partly broken away;

Fig. 13 is a section on line XIII—XIII in Fig. 12;

Fig. 14 is a section on line XIV—XIV in Fig. 12;

Fig. 15 is a view of the detail mutilated in Fig. 12;

Fig. 16 is a sectional view of the detail represented in Fig. 15;

Fig. 17 shows a portion of a safe-door and the handle of the lock with appurtenant parts;

Fig. 18 is a sectional view on line XVIII—XVIII in Fig. 17.

The first embodiment shown in Figs. 1—7 relates to a lock for safes, safe-vaults or the like. In the drawings illustrating this lock, as well as in the following embodiments, only those details are incorporated which are considered necessary for the elucidation of the invention. The lock disclosed, which is fastened to the inside of the safe-door 20 by means of bolts, is provided with a lock-housing formed by a U-shaped part, and the shanks 21 and 22 of this U-shaped part, which form the vertical lateral walls of the housing, are connected by means of the front side 23 secured to the door 20 by means of bolts. At the top and bottom, the two plates 24 and 25 form the horizontal walls of the housing, said plates being inserted in the grooves provided in the side-walls. At the rear, the housing is closed by the cover 26 secured thereto by means of screws. A bolt 27, which is shown in the locking position

in Fig. 1, is adapted to be displaced horizontally in slits provided in the vertical side-walls 21 and 22. The bolt is provided with an obliquely positioned slot 28 engaging a pin 29 which extends from the free end of a lever 30 which is pivoted about the horizontal pin 31. The latter pin which is parallel to the pin 29 extends from the front-side 23 of the lock housing. Projecting from the lever 30 at right angles near the free end thereof is a downwardly directed arm 32. Upon displacement of the bolt 27 from the locking position shown the slot 28 will press the pin 29 and thus also the downwardly directed point of the lever 32 downwards, when the tumblers of the lock permit such a movement, that is to say, when they are properly adjusted to effect unlocking. These tumblers, which are four in number, consist each of two annular parts punched out of pieces of sheet metal of the same thickness, these parts being designated, counted from the cover 26, by 33—34, 33₁—34₁, 33₁₁—34₁₁, and 33₁₁₁—34₁₁₁ respectively. The two rings 33 and 34 of the first mentioned tumbler are shown in plan views in Figs. 4 and 5 respectively, in angular positions corresponding to their initial positions. The ring 34, which forms the tumbler proper, is provided in the outer circumference thereof with a rectangular notch 35, and has on a circle near the inner peripheral portion thereof twelve uniformly distributed holes 36. The ring 33 combined with the ring 34 is intended for turning the latter in the one or the other direction for the purpose of adjusting the same into the unlocking position or for restoring the same into the initial position. In effecting the first-mentioned adjustment the ring 33 is turned in a clockwise-direction by the tooth 37 extending from the inner peripheral portion thereof, when a carrier tooth projecting in the same plane from the operating member is brought into engagement therewith, whereas when restored into the initial position it is turned in the opposite direction by means of the arm 38 extending from the outer peripheral portion thereof, when the arm is actuated by the restoring rod 64 turning in a counter-clockwise direction, as will be described more closely hereinafter. The ring 33 is provided with three axially projecting pins 39 at a mutual angular distance of 120° and located at the same radial distance from the center as the twelve holes 36 in the ring 34. They may thus be fitted into three of these holes, the rings 33 and 34 being then caused to bear on each other and forming together a tumbler the notch 35 of which may be varied in twelve different positions relatively to the tooth 37 and the arm 38 respectively. As will be stated hereinafter, only ten of these combinations, corresponding to the numerals 0—9, will be made use of. When the rings shown in Figs. 4 and 5 are combined without changing their angular positions, the notch 35 will take such an angular position that the tumbler formed corresponds to the adjusting numeral 3. The four tumbler rings 34—34₁₁₁ are mounted with their inner peripheral portions on the flanges 41 extending from the four spacing and bearing washers 42, 42₁, 42₁₁, and 42₁₁₁, the first one being shown in plan view in Fig. 6. These bearing washers, which have the same outer diameter and the same thickness as the rings 34, are provided in their outer peripheral portion with an upwardly directed rectangular notch 43 of the same shape as that of the notch 35. The bearing washers 42—42₁₁₁ are arranged to be carried by arms 44 directed straight upwardly from

the side portion of the notches 43, said arms being provided in their top portions with apertures 45 having a tube 46 extended therethrough, one end of which tube is threaded into the bearing washer 42₁₁₁, and the opposite end of which is screwed fast to a plate 47, which, in turn, is screwed fast to the cover 26 by means of the screws 48. The tube 46 is thrust on to the bolt 49 projecting from the front-side of the lock housing, whereby the necessary rigidness is imparted to the structure. The position of the bearing washers is further defined by the fact that they are mounted with the inner peripheral portion thereof on a cylindrical operating member 50 which is divided along a plane extending through the center thereof into an upper and a lower half, said halves being kept together by means of two bolts 51. The operating member 50 is mounted at its one end in a plate 52 which is secured to the plate 47, and the outline of which is substantially congruous to the outline of the bearing washers 42. In its opposite end the operating member 50 is provided with a U-shaped flange portion 53 of a somewhat increased diameter, which is mounted round the greater portion of its circular outer periphery in a ring 54 screwed fast to the front side 23 of the lock housing. The tube 46, the bolt 49, and the operating member 50 take such a position relatively to each other and in relation to the remaining lock members that, when the bolt 27 is in its locking position, the lower point of the arm 32 will be located right over the notches 43, and with its point close to the outer peripheral portion of the tumbler rings 34. The width of the arm 32 is somewhat less at the end of the arm than the width of the notches 35 and 43, and its thickness in the axial direction is equal to the combined thickness of the four tumblers plus the intervening

40 three bearing washers. The operating member 50 is provided with a cylindrical bore eccentrically arranged relatively to the axis of rotation thereof, said bore having rotatably mounted therein a cylindrical shifting or setting shaft 55, the mounting of which is so adapted that its outer cylindrical surface will contact with the cylindrical surface of the operating member 50. Screwed into the shifting or setting shaft 55 are six carrier teeth 56, 56₁, 56₁₁, 56₁₁₁, 57 and 58, the portion of which projecting radially outside the shaft is of a length somewhat smaller than the width in the radial direction of the flange 41 on the bearing washers. Out of the six carrier teeth, the mutual angular distance of which is 60°, that located nearest the end of the shaft 55 is arranged in a plane lying between the plate 52 and the bearing washer 42 adjacent thereto. Consequently, the tooth 56 will be located in the same plane as the tooth 37 of the tumbler ring 23 nearest the plate 52, which latter tooth it is intended to carry with it in the setting of this tumbler. The succeeding three carrier teeth on the shaft 55 are located in an analogous manner in the same plane as the tooth 37 on the respective tumbler rings 33₁, 33₁₁, and 33₁₁₁. In order that the operating member shall permit of being turned with a carrier tooth in operative position, the bore thereof is provided with annular milled-cut recesses 59, 59₁, 59₁₁ and 59₁₁₁ in the same plane as the respective carrier teeth 56, 56₁, 56₁₁ and 56₁₁₁. The next following fifth carrier tooth 57 is of a somewhat greater diameter than the others, by reason of which its recess 60 is somewhat wider. This carrier tooth is intended to

effect unlocking, that is to say withdrawing of the bolt 27 out of its locking position. To this end, the latter tooth is arranged in the same plane as an unlocking ring 61 the inner peripheral portion of which is provided with a tooth 62 adapted to be entrained in a clockwise direction by the tooth 57. The ring 61 is provided with a radially extending arm 63 located in the same plane as the projections 64 and 65 extending from the lower side of the bolt, said projections being adapted to be actuated by the arm 63 for the purpose of effecting unlocking and locking respectively. The ring 61 is screwed fast to the side of a toothed ring 66 which is mounted on the one flange of a bearing washer 67 of substantially the same shape as that of the washer 42 but provided with flanges on both sides, whereby the section thereof obtains the shape of a T. The bearing washer 67, which is carried by the bolt 49, has another toothed ring 68 mounted on its second flange, the rim of said latter ring being equal to that of the toothed ring 66 and having on its inner peripheral portion a tooth, not shown in the drawing, adapted to be entrained by the sixth carried tooth 58 and located consequently in the same plane as the latter. The toothed ring 66 meshes with a smaller gear wheel 69 mounted on the pin 70. The gear wheel 69 meshes in turn with another gear wheel 71 of the same size in a plane between the toothed rings 66 and 68, the gear wheel 71 being mounted on the pin 72. The gear wheel 71 meshes in turn with the toothed rim 68 which consequently when turned always moves in a direction opposed to that of the toothed rim 66 and the ring 61 actuating the bolt of the lock. The toothed ring 68 has for its object to aid in restoring the tumblers into their initial positions. This is effected in the following manner: the carrier tooth 58 of the operating member turns the toothed ring 68 in a clockwise direction, the toothed ring 66 and the unlocking ring 61 rigidly connected therewith being then caused to turn by the same angle in the opposite direction. A restoring rod 84 extending from the arm 63 axially along the external peripheral portion of the tumblers is then brought into engagement with the arms 38, whereby the tumblers are turned in a counter-clockwise direction into their initial positions, which are reached when the rod 84 strikes against the arms 44 of the bearing washers, which corresponds to the angular position of the arms 38 shown in Fig. 5. The teeth 37 of the tumblers will then take the initial position shown in the same figure, which corresponds to a turning movement of 40° in a clockwise direction from the horizontal position.

The turning of the setting or shifting shaft 55 by a sixth revolution in a clockwise direction at each oscillation of the operating member 50 of at least 35° for the purpose of shifting the carrier teeth is effected by a pawl and ratchet device comprising the pawl 74 actuated by the spring 73, said pawl being in turn adapted to engage the six ratchet teeth of the ratchet wheel 75 secured to the end of the shaft 55. As will appear from Fig. 3, the pawl 74 is prevented by the abutment 83 from carrying more than one tooth at a time along with it. A pawl 86 actuated by the spring 85 is pivoted about the pin 82 screwed into the operating member 50, and this pawl prevents the shaft 55 from turning in a counter-clockwise direction relatively to the operating member.

The oscillatory movements of the operating

member are produced by means of a finger dial 77 which is shown in Fig. 7 to a somewhat smaller scale than the other parts. This finger dial, which is substantially of the same shape as the finger dials used in connection with automatic telephony, is provided with ten finger holes having the designations 0 to 9. The finger holes are arranged at a mutual angular distance of 30°, and the angular distance from the 0-hole to the finger stop 78 is 55°. When turned in a clockwise direction the finger dial is counteracted by a spiral spring 79 which returns the same into the initial position shown in Fig. 7, as soon as the force turning in a clockwise direction ceases. The finger dial 77 is secured to the spindle 80 extending through the door 20, the spindle being provided with a stop ring 81 on the inside of the door. Said stop ring is provided with an eccentrically located hole engaged by the pin 82 screwed into the operating member, so that the finger dial and the operating member will perform the same angular movements. The initial position of the finger dial is reached when the abutment 83 of the flange 53 strikes against the pawl 74.

The mode of operation of the lock described will appear from the following account. It is supposed that the so-called combination number of the lock is 3 7 9 1, which involves that, in order to permit displacement of the bolt of the lock out of locking position, the said four numerals will first have to be "struck" by means of the finger dial 77 in the order stated. It is assumed for the sake of simplicity that, prior to the striking of said combination number, the tumblers of the lock are in their initial positions, the carrier tooth 56 for the first tumbler having then to be in its operative position, that is to say in a horizontal position to the right in Fig. 1, i. e. the same position which is taken by the carrier tooth 57 in Fig. 1. Now, when the first numeral of the combination, a three, is struck, the finger dial is first turned by the angle between the finger holes 3 and 0, namely 90°, and then by the angle between the initial position of the 0-hole and the finger stop, namely 55°, that is to say 145° all in all. However, the carrier tooth 56 engages the tooth 37, as stated hereinbefore, only upon a turning movement of 40°, and consequently the turning movement of the tumbler 33-34 in a clockwise direction, when the three is struck, will be 105° only. The notch 35, the initial position of which is shown in Fig. 4, will thus turn by 105° in a clockwise direction and will consequently take the topmost position right underneath the point of the arm 32. Then, when the finger dial returns into its initial position, the pawl 74 during the last turning movement by 35° in a counter-clockwise direction will turn the shifting or setting shaft 55 by 60° so as to bring the next carrier tooth 56 into operative position for engagement with the tooth 37 on the succeeding tumbler 33-34. This tumbler, which is adjusted by striking the numeral 7 by the finger dial, has its notch 35 in the position shown by dotted lines in Fig. 4. When the seven is struck on the finger dial, this tumbler will be turned in a clockwise direction so that its notch 35 is caused to take the exact topmost position. In an analogous manner, the two remaining tumblers are then adjusted by striking the nine and the one on the finger dial. The locking members then take the mutual positions shown in Fig. 1. Now, the tooth 57 intended for the unlocking operation is in its op-

erative position. When the nine was struck, the arm 38₁₁ of the tumbler 33₁₁—34₁₁ moved the restoring rod 84 and thus the ring 61 into the angular position shown in Fig. 1, with the unlocking arm 63 off the abutment 64 on the bolt 27 of the lock by an inconsiderable angle only. To effect unlocking, the numeral 9 is now struck on the finger dial, the carrier tooth 57 then moving the bolt of the lock out of its locking position during the last 30 degrees of the turning movement of said tooth in a clockwise direction, the arm 32 being then depressed into the properly adjusted notches of the tumblers, whereupon the door may be opened. After the door has been shut again, locking is effected by again striking the nine on the finger dial. The sixth carrier tooth 58 will then turn the toothed rim in a clockwise direction, whereby the toothed rim 66 and thus the unlocking ring 61 will be turned by the same angle in a counter-clockwise direction. Here, the bolt 27 is first brought into locking position by its abutment 65 on the arm 63 being moved to the left in Fig. 1, whereby the arm 32 is simultaneously raised out of the notches of the tumblers. Upon a continued turning movement in a counter-clockwise direction, the restoring arm 84 moves all of the tumblers into the initial position in the manner hereinabove described. When the lock is to be unlocked again, the procedure repeats itself in the manner set forth hereinbefore.

It is conceivable, however, that an unauthorized person has tampered with the lock after it was locked the last time by an authorized person. As the combination is unknown, the chances are very small to find the proper combination among the 10,000 possible combination numbers, and consequently the efforts will result in that the lock remains locked, but with the locking members in such a position that an authorized person cannot unlock immediately by striking the proper combination. It then becomes necessary to reset the locking members into their proper initial positions, that is to say, in this case with the carrier tooth 56 for the first tumbler in its operative position, so that unlocking can be commenced with by striking the three. To this end nines are struck repeatedly on the finger dial as far down as to the finger stop, until it occurs that the hole of the nine cannot be moved further than about 30° from the finger stop, which shows that the bolt of the lock is actuated in vain to effect unlocking. One then knows that the next nine which is struck will perform resetting of the tumblers, whereupon the proper initial position is reached. After that the proper combination is struck.

If the combination number of the lock has become known to unauthorized persons, recombination of the two-part tumblers may be effected readily for any number comprising four numerals. For this purpose the lock is unlocked and the door opened in the ordinary manner, so that the rear side of the lock housing is rendered accessible. After that the nine is struck on the finger dial for resetting, but the finger dial is not permitted to return into its initial position, but is fixed with the hole of the nine adjacent to the finger stop, for instance by means of a steel wire or the like. All of the tumblers have now been restored, the arms 38 then lying just inside the outline of the arms 44 on the bearing washers. The carrier tooth 58, however, for the toothed ring 68 is still in its

operative position. After that all four tumblers are taken out together with their four bearing washers by loosening the screws 48 and by pulling the plate 47 and the plate 52 connected therewith straight rearwardly, the tumblers and the bearing washers then sliding off the operating member 59 and the bolt 49. Now, the operating member will be carried only by the bearing washer 67 and the ring 54. The tube 66 is then unscrewed both from the bearing washer 42₁₁ and from the plate 47, after which all tumblers become free and permit of being recombined in the desired manner, it being of course necessary not to forget to note down the new combinations accurately. The tumblers and bearing washers are then remounted on the operating member and the bolt 49, and the plate is screwed fast by means of the screws 48. The finger dial having been loosened and permitted to return into its initial position the lock is ready for use in its new combination.

The form of embodiment shown in Figs. 8-11 also refers to a lock for safes or the like. A number of the details of the construction of this lock are identical with corresponding details in the above described first embodiment, and for this reason the same designation numerals with a prime (') annexed thereto are used for corresponding parts in the description of this second embodiment. The combination number for this latter lock is also taken to be 3 7 9 1.

As in the preceding embodiment, this second lock also has a housing screwed to the inside of the door 20', said housing being provided with vertical sidewalls 21' and 22' united by means of the front wall 23'. The housing is closed at the rear by means of the cover 26' outside of which the cover 47' is secured by means of screws. Secured to the inside of this cover is a plate 52' on a level with the cover 26', said plate forming the bearing for a circular disk 100 forming the inner termination of the operating member 101 consisting of a cylindrical sleeve (Fig. 10). This operating member is provided with two longitudinally extending and diametrically opposed slits 102 and 103 located in a horizontal plane in the initial position shown in Figs. 8 and 10. In its end portion bearing on the door 20' the operating member 101 is provided with a radially extending inward flange 104 into the center of which is threaded a sleeve 105 secured by means of the screw 106. The sleeve 105 is mounted in the door 20' and is provided on the front side of the latter with a flange portion 107 which continues in a cylindrical sleeve 108 (Fig. 9) of the same cross section as that of the sleeve 101, and which is provided with similar and equally located slits 109 and 110 (Fig. 9), and which is closed at the front by means of the cover 111. The sleeve 108 is located at the center of a cylindrical housing 113 secured to the front side of the door by means of the screws 112 and closed at the front by means of the cover 113. Mounted on the outside of the sleeve 101 are four bearing washers of identically the same type as in the preceding embodiment. In Figs. 8 and 10, the second in order, counted from the cover 26', is designated by 42'1, while its upwardly directed arm is denoted by 44'1. The four bearing washers constitute the bearing means for four tumblers of identically the same type as those used in the preceding embodiment. Figs. 8 and 10 illustrate the ring 38'11 pertaining to the third tumbler, with the restoring arm 38'11 and the adjusting abutment 37'11. For the ad-

justment of the tumblers in accordance with the principle of the invention there are provided four radially displaceable carrier teeth, one of which that designated by 114 in Figs. 8 and 10 is in its operative initial position, inasmuch as the same is displaced radially outwards so as to protrude outside the cylindrical surface of the sleeve 101. The tooth 114 projects from a round disk 115 provided with an annular slot 116 entering axially from the side and arranged to be actuated by a pin 117 extending axially and eccentrically from a round disk 118 which is secured to the shaft 119 by means of a tongue fitting the longitudinally extending slot 120 in said shaft. The tooth 114 and the arm 121 projecting in a diametrically opposite direction thereto are displaceably fitted into the respective slots 103 and 102 in the sleeve 101. The slot 116 in the disk 115 consists of a circular arc of 240° united by means of an arc of less curvature. During a turning movement of 240° of the shaft 119 in a clockwise direction relatively to the sleeve 101 the pin 117 will keep the tooth 114 retracted inside the jacket surface of the sleeve 101. During the succeeding turning movement by 60° the tooth will project into operative position, as shown in Figs. 8 and 10, and during the remaining turning movement of 60° the tooth will again be retracted. The four pins effecting the shifting of the carrier teeth are arranged at a mutual angular distance of 60°. The shaft 119 is continued within the sleeve 105 by a larger shaft portion 122 which, in turn, is continued within the sleeve 108 by a shaft 123 of the same section as that of the shaft 119 and provided with a similar and equally located slot 124. The shaft 123 is extended through a hole at the center of a finger dial 125, so that the outer end thereof will lie in the same plane as the outer side of the finger dial.

As in the preceding embodiment, this second lock is also provided with an unlocking ring 61' secured to the side portion of a toothed ring 66' which is in connection with a similar toothed ring 68' over two smaller gear wheels, by reason of which the two toothed rings when turned will move in opposite directions at the same angular velocity. The bolt of the lock and the parts cooperating therewith are identical with the corresponding parts in the preceding embodiment.

To effect the turning movement by 60° of the shifting or setting shaft 119, 123 for operation in a clockwise direction relatively to the operating member 101 for each oscillation of at least 35° of the finger dial there is provided a ratchet device, shown in Fig. 11 and consisting of the wheel 126 provided with six ratchet teeth, said wheel being secured on the shaft 123, and consisting also of the pawls 127 and 128, the first one of which is pivoted about a pin 129 extending from the cover 111 secured to the sleeve 108, and is actuated by the spring 130, while the latter pawl is actuated by the spring 131, and is pivoted about the pin 132 extending from the cover 153 secured to the casing 113. The finger dial 125 is secured to the cover 111 by means of the three screws 133 extending through the half-moon-shaped plate 134, the point 135 of which prevents the pawl 128 from advancing more than one tooth at the time on the wheel 126. The initial position of the finger dial 125 will be reached when the pawl 128 strikes against the abutment 136, as shown in Fig. 11. The contrivance above described for turning the shifting or setting shaft 119, 123 operates in principle in the same man-

ner as the corresponding device in the preceding embodiment. It should be noted in this connection that the locking device described is located in its entirety on the outside of the door where it is readily accessible by loosening the finger dial. Hereby the mechanism located inside the door becomes altogether relieved of springs of any kind. The finger dial 125, its finger stop 137 and its return spring 138 have exactly the same functions as the corresponding parts in the preceding embodiment.

It is believed to be understood from the description hereinbefore that this latter lock may be operated in identically the same manner as the preceding lock, that is to say, all operations take place by oscillating the finger dial in accordance with certain rules laid down for the lock. This latter lock, however, is provided with a contrivance enclosed within the casing 113 and adapted to facilitate the setting of the four tumblers. To this contrivance pertains the sleeve 103 with the four carrier teeth arranged therein, said teeth being of identically the same construction as those provided in the sleeve 101 (114 and others). These four carrier teeth, out of which the third one, counted from the door in Figs. 8 and 9, is shown in operative position in exactly the same manner as the tooth 114, and which is designated by 139 in said figures, correspond to the respective carrier teeth for the setting of the tumblers and are arranged to move in exact synchronism with the latter. They are each adapted to entrain one of four stepped wheels, of which the wheel designated by 140 in Fig. 8 is entrained by the tooth 139 at the next succeeding oscillation of the finger dial 125 by the fact that the same will in a clockwise-direction actuate the abutment 141 on the ring 142 secured to the side of the stepped wheel 140. The four stepped wheels, which all are of the shape of the stepped wheel 143 shown in Fig. 9, are each provided with ten steps, of which that denoted by 144 in Fig. 9 has the smallest radius. This step corresponds to the numeral 0 on the finger dial, while the other steps correspond in due order to the numerals 1 to 9. The step corresponding to the numeral 9 is designated by 145, and the next succeeding abutment 146 with the greatest radius is adapted to be actuated for restoring the stepped wheel into the initial position shown in Fig. 9, in which position it bears with its radial edge 147 on a rod 148 extending from the wall of the casing 113 bearing on the door. The returning of an adjusted stepped wheel takes place on the return stroke of the oscillation whereby it was adjusted immediately before, and such returning movement is arranged to be performed by an axially extending rod 149 projecting perpendicularly from the outer end of an arm 154 extending radially from the cover 111. It will appear from the statements hereinbefore that when a tumbler is entrained by a carrier tooth the stepped wheel corresponding to said tumbler will be entrained exactly at the same time by its carrier tooth through the same angle. In order accurately to define this angle to correspond to the combination numeral for the tumbler in question, a form or key 150 will be introduced radially to the center of the four stepped wheels. As will be seen from Figs. 8 and 9, where said key is shown in the proper position, the same is constituted by a rectangular plate provided with an annular handle, out of which plate are punched four slots of a somewhat greater width than the thickness of the

stepped wheels and located at the same mutual distance as the stepped wheels. The depth of the slots corresponds to the combination numerals in such manner that, when the key is inserted into its proper position, the slot adjacent to the door, which is denoted by 151, will stop the fourth step of the corresponding stepped wheel, whereby the corresponding tumbler is turned through an angle corresponding to that obtained when the numeral 3 is struck by the finger dial. Analogously, the third slot 152 has a depth corresponding to the numeral 9, and so forth. When the lock is operated with the aid of the key above described, the combination number need of course not be committed to memory. However, since nines may occur in this number, nines should always be struck on the finger dial. As the outer end of the setting shaft 123 is visible with its slot at the center of the finger dial, it will be found suitable to indicate the position of the slot on the finger dial, when it is in its initial position, by a mark, when the lock is in its initial position for the adjustment of the first tumbler. When unlocking is to be effected, it will then only be necessary to strike nines until the said slot and mark coincide, whereupon either the combination number will be struck by the finger dial, or the key will be inserted into position, and four nines being struck, after which the next succeeding nine moves the bolt of the lock out of locking position.

Recombination of the tumblers for another combination number is effected in this latter lock in exactly the same manner as in the preceding embodiment. Naturally, a new combination number also calls for a new key.

The arrangement for operating the lock by the use of a form or key may obviously also be applied in the preceding construction of lock shown in Figs. 1 to 7.

Finally, Figs. 12 to 18 show a third simpler form of embodiment of a locking means in accordance with the principle of the invention. The housing 160 of this lock has its front wall 166 secured on the inside of the door by means of the four corner screws 162-165, and the four side walls pressed integral, with the rear wall 167 secured by means of the above-mentioned screws 162-165 to the front wall. The lock bolt 168, the extremity of which is bevelled off outside the housing, is guided in a slit in the one vertical side wall and by two bolts 169 and 170 projecting from the front wall 166 and engaging the respective slits 171 and 172 in the lock bolt 168. The latter is retained in the locking position shown in Fig. 12 by a spiral spring 173 which is housed within a cylindrical sleeve 174 welded to the upper edge portion of the lock housing, and the one end of which bears on a pin 175 projecting perpendicularly from the lock bolt 168. The opposite end of the spring 173 bears on another pin 176 extending at right angles from the shorter, upwardly directed arm 177 of a two-armed lever which is pivoted on the pin 178, and the downwardly depending longer arm of which is constituted by the toothed segment 179, the construction and function of which will be described hereinafter. In the position shown, the arm 177 bears on the screw 162. Displaceably fitted between the lock bolt 168 and the rear wall is a slide-piece 180 which is also guided by the two bolts 169 and 170 engaging corresponding slits therein, and which is provided with a pin 181 engaging the slit 172 in such manner that the slide-piece will upon

displacement in a direction toward effecting unlocking entrain the lock bolt against the tension of the spring 173, whereas the lock bolt may be displaced independently of the slide-piece when the door is shut. The slide-piece is provided with a notch 182 in the lower edge thereof adjacent to the rear wall 167, said notch being adapted to be engaged by a tooth 184 projecting radially from the unlocking disk 183 (Fig. 13). The disk 183, bearing with one side thereof on the rear wall 167, is pivotally mounted on a cylindrical sleeve 185 which is screwed onto a flange portion 186 on the inside of the rear wall 167. Furthermore, four circular tumblers are rotatably mounted on the sleeve 185, said tumblers being designated, counted from the disk 183, by 4, 1, 2 and 3 respectively. These tumblers, which consist of sheet metal stampings of a thickness of a few millimeters, are each provided with two radially extending teeth, i. e. one shorter adjusting tooth and another longer restoring tooth. In Fig. 12, which shows the tumblers in their initial position, said teeth are denoted by 187 and 188 respectively. By means of five circular spacing members 189 non-rotatably mounted on the sleeve 185 each individual tumbler is prevented from being turned otherwise than through the actuation of the teeth 187 and 188. Each tumbler is provided with a notch of uniform width extending radially inwards from the peripheral portions thereof, the angular position of which notch is determined relatively to the setting tooth 187 by the numeral of the combination number of the lock corresponding to the respective tumblers, said number comprising four numerals in the present case in view of four tumblers being provided. For this lock, too, the combination number is taken to be 3791, by reason of which the notches in the initial position shown in Fig. 12 take the angular positions designated in Fig. 12 by 1, 2, 3 and 4, said numerals corresponding to the designations of the respective tumblers. With properly adjusted tumblers according to the combination number the four notches should take a horizontal position, as shown at 190, that is to say, the notches should register with the notches 191 provided in the spacing members 189. In this position it will be found possible to move the lock bolt out of locking position. This is so for the reason that the horizontal stop plate 192 projecting from the downwardly depending arm 193 of the lock bolt extends into the registering notches of the tumblers 4. Again, should a single tumbler be incorrectly set, the lock bolt cannot be displaced out of locking position.

The operation of the lock, that is to say the adjustment and restoring of the tumblers into the initial position, the displacement of the lock bolt out of locking position, and the shifting of the latter is effected solely with the aid of oscillations, i. e. by reciprocating angular movements of a single operating member or manoeuvring member. This manoeuvring member consists of the door-handle 194 which is retained by means of the screw 195 on the square-head 196 of the lock spindle 197. This lock spindle is journaled in a cylindrical flange portion 198 on the front wall 166 as well as in the previously mentioned flange portion 185 on the rear wall 167. Furthermore, the hub 199 of the door-handle 194 is mounted on the outside of a cylindrical flange portion 200 on the circular fitting 201. A spiral spring 202 about the spindle 197 is so arranged as to tend to turn the spindle in a counter-clock-

wise direction. In Fig. 17, the door-handle is shown in the starting position, a pointer 203 on the hub 199 being then opposite the left division-line, designated by x , of a scale 204 on the fitting 201. From this position, the door-handle may be adjusted through a turning movement in a clockwise direction against the tension of the spring 202, with the pointer opposite any one of the numerals 0-9, corresponding to the numerals of the combination number. With insufficient illumination, however, adjustment cannot take place with the aid of the scale 204, the adjustment being effected in this case by the perception of touch. To this end the door-handle is provided with an appendage extending obliquely downwards to the left, said appendage, which is designated by 205, being provided on the front side thereof with a spherical cup 206, the bottom portion of which is bisected by a cylindrical slot 207 cutting into the appendage 205 on the side thereof facing the door. Protruding into this slot 207 is a cylindrical segment 208, without abutting against the surfaces of the slot. The segment 208, which extends perpendicularly from the edge portion of the fitting 201, is provided with rounded teeth 209 in the outer edge portion thereof, out of which teeth the ten teeth of the group within the angle 210 are at the same angular distance from each other as the division-lines 0-9 of the scale 204 to which the teeth 209 correspond in due order. The tooth 211 at the bottom of the segment 208 corresponds on the scale 204 to the division line for the starting position designated by x . The teeth 209, 211 protrude by a few millimeters through the slot 207 at the center of the cup 206, and may thus be distinguished by feeling and counted. When effecting adjustment in darkness one thus places one's right hand with the inside of the point of the thumb in the cup 206 and with the other four fingers on the upper side of the door-handle 194. In the starting position shown in Fig. 17, the tooth 211 corresponding to the division line x on the scale 204 is then felt by the thumb as protruding at the center of the cup. For example, if the number 7 is to be struck, the door-handle is first depressed by the angle 212 (Fig. 17) until the first tooth 209 in the group, corresponding to the numeral 0 on the scale, has been reached. The turning movement is then continued, and at the same time the teeth are counted which are felt by the thumb as passing, until the seventh tooth has been reached, counted from the nought tooth, whereat the turning movement is interrupted with the seventh tooth at the center of the cup 206. The pointer 203 then points to the division-line 7 of the scale 204 which, however, cannot be read off in the darkness. The door-handle is then permitted to return into the starting position under the action of the spring 202. The movement described is mediated by means of the lock spindle onto the arm 213 which is shown in section in Figs. 13 and 16 and in plan view in Figs. 12 and 15. In Fig. 12, the lower portion of the arm 213 is cut away, in order that the adjusting roller 214 provided thereon with its five setting teeth 1', 2', 3', 4' and 5' and the shuttle-like pawl 215 shall become visible. The arm 213 which is punched out of sheet-metal is secured on a square-head 216 of the lock spindle 197, and the one side thereof abuts against the outer wall 166. Projecting at right angles on its opposite side near the peripheral portion thereof is a pin 217 on which the adjusting roller 214 is rotatably mounted, said roller extending in the axial di-

rection to the rear wall 167. As illustrated in Fig. 16, the five teeth of the roller 214 are located each in one plane. In a radial direction, they are located at the same angular distance, i. e. 72°. The roller 214 is prevented from turning in a clockwise direction by the pawl 215 which is displaceably guided by two bolts 218 and 219 screwed into the arm 213, the portion of which bolts projecting from the arm 213 is bevelled off so as to make the section semi-circular. The bolts 218 and 219 are fitted into milled-out portions in the pawl 215 which is actuated in a direction toward the roller 214 by a spiral spring 220 housed within a bore in the pawl. The point 221 of the pawl extends axially all over the length of the roller 214 and may thus actuate the five setting teeth 1'-5' in due order. Furthermore, a rod 222 extends from the arm 213 in an axial direction, said rod being intended to restore the tumblers into the initial position shown in Fig. 12 by actuating the teeth 188 of the tumblers, which is effected when the door-handle 194 is turned in a counter-clockwise direction from the position shown in Fig. 17. The teeth 188 having been returned in their entirety the rod 222 takes the position shown by dotted lines at 222', the setting teeth 187 then abutting against the corner of the lock bolt, as shown in Fig. 12. For certain practical reasons the order of the adjustment of the tumblers is not regular. First of all the tumbler 1 is adjusted, which is the second in order counted from the rear wall 167. This tumbler corresponds to the numeral 3 of the combination number and has its notch 1 in such an angular position that the tumbler will have to be turned by four division-lines, in order that the notch shall take a horizontal position, as shown at 190. This turning movement is performed by the tooth 1' on the adjusting roller 214 which in Figs. 12, 15 and 16 takes the original position for the adjustment of the tumblers. In this position the tooth 3' is turned outwardly towards the toothed segment 179. When the door-handle is turned downwardly (in a clockwise direction), the tooth 3' will strike against the oblique tooth 223 at the point of the toothed segment 179, whereby the roller 214 is turned by a fifth of a revolution, the pawl 215 being then pressed back by the tooth 5' out of engagement with the tooth 4' and moving instead into engagement with the tooth 5'. The tooth 1' will then bear on the setting tooth 187 of the tumbler 1. Upon continued turning movement of the door-handle in a clockwise direction by an angle equal to the distance between two division-lines on the scale 204 the pointer has reached the division-line 9 on the scale, that is to say, the door-handle has made the adjusting movement that would be required for the adjustment of a tumbler corresponding to the numeral 0. (Naturally, a tumbler corresponding to the numeral 0 in a combination number should not be adjusted already in the initial position). The turning movement in a clockwise direction is now continued further by three division-lines, so that the pointer will point exactly to the numeral 3 on the scale 204. In darkness, counting is effected with the aid of the contact between the thumb and the teeth of the segment 208. When the tooth for 3 is felt to be exactly at the center of the cup, the tumbler 1 is adjusted. The door-handle is then permitted to return into the initial position under the influence of the spring 202. The tension of this spring 75 is so adapted that the tooth will be able to force

away the tooth 223 of the segment 179 against the tension of the spring 173. The arm 213 and thus the door-handle are arrested in the initial position by the bevelled abutment 224 (see Fig. 15) striking against the oblique surface 225 at the point of the segment 179. As will be seen, this surface is considerably "steeper" than the oblique surface 223, and consequently the spring 202 will not be able in this case to press away the segment 179. Now the door-handle is again turned downwardly (in a clockwise direction) for adjusting the next tumbler 2, with the notch 2, corresponding to the numeral 7. This tumbler is the third one counted from the rear wall 167. The adjustment, which is performed by means of the tooth 2', takes place analogously to the previously described adjustment of the tumbler 1. After that, the third tumbler 3 is adjusted in an analogous manner, said tumbler being adjacent to the arm 213, and, finally, the fourth tumbler 4 is adjusted, which is on the opposite side next to the unlocking disk 183. This latter tumbler having been adjusted, the tooth 2' is directed toward the segment 179. On having returned into the initial position and upon repeated turning of the door-handle in a clockwise direction, the tooth 5' is brought into operative position relatively to the tooth 187 on the unlocking disk 183. Upon a continued rotary movement of the handle in a clockwise direction the tooth 184 will therefore displace the slide-piece 180 and thus also the lock bolt 168 out of locking position, the plate 192 then sliding into the four registering notches 1', 2', 3', and 4' in the tumblers. When the door-handle is then permitted to return toward the initial position, such position is not reached, however, inasmuch as the tooth 3', which has now been turned back into the angular position shown in Figs. 12 and 15, strikes against the steep surface on the tooth 225 (at 226 in Fig. 14). As the power of the spring 202 is not sufficient to press back the segment 179, the door-handle will not move up into the initial position. The lock will consequently remain unlocked. To restore the lock into locking position, that is to say into the initial position shown in Fig. 12, the door-handle will be turned in a counter-clockwise direction (upwardly), the tooth 3' then pressing out the segment 179. Upon continued rotary movement in a counter-clockwise direction the abutment 224 (Fig. 15) moves past the oblique surface 225. The turning movement is continued until the restoring teeth 188 and thus the rod 222 are arrested by the corner of the lock bolt. The door-handle is then turned back in a clockwise direction, so that the abutment 227 (Fig. 15) is caused to press out the toothed segment 179 and moves past the tooth 225, whereupon the locking position shown in Fig. 12 has been reached. The adjusting roller is already before in its original position, and consequently it will be possible to unlock the lock anew by striking the combination.

It may occur, however, that unauthorized persons have tampered with the lock during futile efforts to unlock it, and the members of the lock have then been left in unknown positions. When an authorized person desires to unlock the lock, there is every reason to suspect that the adjusting roller does not take its original position. Therefore, the lock is so arranged that it will be possible under all circumstances to restore the adjusting roller 214 into the original position, that is to say with the tooth 5' turned inwardly

towards the center of the tumbler, and with the tooth 3' turned outwardly towards the segment 179, by only turning the door-handle in a counter-clockwise direction until the movement is stopped by the restoring teeth 188 and thus the rod 222 being arrested by the lower corner of the lock bolt. The tooth directed toward the segment 179, which may be any one of the five teeth 1'-5' on the roller 214, is then moved up above the tooth 4' on the segment 179. When the door-handle is then moved down into the initial position, the abutment 227 then pressing back the tooth 225 of the segment, that one of the teeth 1'-5' which is directed toward the segment 179 will strike against that one of the teeth 1'', 2'', 4'' or 5'' which is in the path thereof, and hereby the roller 214 will be turned by the number of steps required to cause the tooth 5' to stand in the original position. In case the tooth 3' is directed toward the segment 179 and the tooth 5' is consequently already in its original position, no resetting of the roller 214 is required, and for this reason the segment 179 is not provided with any tooth in the zone 228 within which the tooth 3' moves along the segment 179.

If it is desired to recombine the tumblers or to insert new tumblers with other numerals, it is only necessary to loosen the rear wall 167, whereupon the tumblers may be removed and the desired alteration undertaken.

What I claim is:

1. In a combination lock, a plurality of tumblers adapted to control a bolt, a setting member movable only by oscillation, and carrier means associated with said setting member and adapted to be set in relation to said member by the oscillatory movement thereof, said carrier means being movable only in a plane at right angle to the axis of oscillation of said setting member and comprising in combination with a plurality of carrier members adapted to set said tumblers in accordance with the combination of the lock, a carrier member adapted to restore said tumblers into initial position and a carrier member adapted to unlock said bolt, whereby the lock is rendered operable by means of a single setting member.

2. In a combination lock, a plurality of tumblers adapted to control a bolt, a setting member movable only by oscillations, a rotatable member carried by said setting member and adapted to be rotated by the oscillatory movement thereof, and carrier means associated with said setting member and said rotatable member and adapted to be set in relation to the setting member by the oscillatory movement thereof, said carrier means being movable only in a plane at right angle to the axis of oscillation of said setting member and comprising in combination with a plurality of carrier members adapted to set said tumblers in accordance with the combination of the lock, a carrier member adapted to restore said tumblers into initial position and a carrier member adapted to unlock said bolt, whereby the lock is rendered operable by means of a single setting member.

3. A combination lock according to claim 2, wherein said rotatable member is movable through a given angle relatively to the setting member by the oscillatory movement thereof in the one direction, and wherein means are provided to hold said rotatable member stationary relatively to said setting member at the oscillatory movement thereof in the opposite direction.

4. A combination lock according to claim 2,

wherein said rotatable member is arranged eccentrically in relation to the axis of oscillation of the setting member.

5. A combination lock according to claim 2, wherein said rotatable member is arranged eccentrically in relation to the axis of oscillation of the setting member and is movable through a given angle relatively to said setting member by the oscillatory movement thereof in the one direction, and wherein means are provided to hold said rotatable member stationary relatively to the setting member at the oscillatory movement thereof in the opposite direction.

6. A combination lock according to claim 2, wherein said carrier members consist of projections rigidly secured to the rotatable member.

7. In a combination lock, a plurality of tumblers adapted to control a bolt, a setting member movable only by oscillations, a rotatable member carried by said setting member and adapted to be rotated by the oscillatory movement thereof, a plurality of pins mounted in said setting member to slide in planes at right angles to the axis of oscillation thereof, and cam means carried by said rotatable member to actuate said pins, said pins comprising a plurality of pins adapted to set said tumblers in accordance with the combination of the lock, a pin adapted to restore said tumblers into initial position and a pin adapted to unlock the bolt, whereby the lock is rendered operable by means of a single setting member.

8. A combination lock according to claim 7, wherein said rotatable member is movable through a given angle relatively to the setting member by the oscillatory movement thereof in the one direction, and wherein means are provided to hold said rotatable member stationary at the oscillatory movement of the setting member in the opposite direction.

9. In a combination lock for doors and the like, a locking mechanism adapted to be arranged inside the door and comprising, a plurality of tumblers adapted to control a bolt, a setting member movable only by oscillations, a rotatable member carried by said setting member and adapted to be rotated by the oscillatory movement thereof, carrier means associated with said setting member and said rotatable member and adapted to be set in relation to said setting member by the oscillatory movement thereof, said carrier means comprising a plurality of carrier members adapted to set the tumblers in accordance with the combination of the lock, a carrier member adapted to restore the tumblers into initial position and a carrier member adapted to unlock the bolt, said setting member and said rotatable member having each an extension adapted to project outside the door, said rotatable member being movable through a given angle relatively to said setting member by the oscillatory movement thereof in the one direction, ratchet wheel means connected to the extension of the rotatable member to hold said member stationary relatively to said setting member at the oscillatory movement thereof in the opposite direction, and a manoeuvring member connected to the extension of said setting member.

10. In a combination lock for doors and the like, a locking mechanism adapted to be arranged inside the door and comprising, a plurality of tumblers adapted to control a bolt, a setting member movable only by oscillation, a rotatable member carried by said setting member and adapted to be rotated by the oscillatory

movement thereof, carrier means associated with said setting member and said rotatable member and adapted to be set in relation to the setting member by the oscillatory movement thereof, 5 said carrier means comprising a plurality of carrier members adapted to set the tumblers in accordance with the combination of the lock, a carrier member adapted to restore the tumblers into initial position and a carrier member adapted to unlock the bolt, said setting member and said rotatable member having each an extension adapted to project outside the door, additional carrier members associated with said extensions and corresponding respectively to the tumbler 10 controlling carrier members of the locking mechanism and adapted to be set in accordance with the latter, stop members carried by the extension of said setting member and adapted to control the oscillatory movement thereof, a key 15 formed in accordance with the combination of the lock and insertable in the path of movement of said stop members to control the movement thereof, and a manoeuvring member connected to the extension of said setting member.

25 11. In a combination lock, a plurality of tumblers adapted to control a bolt, a setting member movable only by oscillation, carrier means mounted on said setting member and comprising a carrier roller arranged eccentrically in the relation to the axis of oscillation of said setting member and adapted to be rotated by the oscillatory movement thereof, said roller carrying means to set the tumblers in accordance with the combination of the lock and means to restore 30 the tumblers into initial position, said carrier means also comprising means to unlock the bolt, whereby the lock is rendered operable by means of a single setting member.

12. A combination lock according to claim 11, 40 wherein said carrier roller and said tumblers are provided with co-operating teeth, and wherein a pawl and ratchet mechanism is provided engaging the teeth of said roller to rotate same step-wisely by the oscillatory movement of the setting member.

45 13. A combination lock according to claim 11, wherein said tumblers and said carrier roller are provided with co-operating teeth, the teeth of said carrier roller projecting radially in interspaced planes, and wherein a pawl and ratchet mechanism is provided adapted to engage the teeth of the carrier roller to rotate same step-wisely by the oscillatory movement of the setting member, said mechanism comprising a toothed member having a tooth adapted to engage all the teeth of the roller and a plurality of teeth arranged in interspaced planes coinciding with the planes in which the teeth of the roller are arranged so that the latter teeth of the toothed member are each adapted to be brought into engagement with a tooth on the roller by the oscillatory movement of the setting member to restore said roller into initial position.

60 14. In a combination lock according to claim 11, the provision of a door handle carrying said setting member and also carrying one of the co-operating parts of a pointer and scale indicator to indicate the angles of oscillation of the setting member in correspondence to the digits of the combination number of the lock, and separate indicating means operable by the perception of touch to permit control of said angles in darkness.

75 15. In a combination lock, a plurality of tum-

blers adapted to control a bolt, an oscillatory setting member, a carrier roller carried by said setting member and arranged eccentrically in relation to the axis of oscillation thereof, said carrier roller carrying means to set the tumblers in accordance with the combination number of the lock and means to unlock the bolt, means to turn said carrier roller stepwisely by the oscillatory movement of the setting member to bring said tumbler setting means and said bolt unlocking means into operative position to actuate the tumblers and the bolt, respectively, and means to restore said tumblers into initial position.

16. A combination lock according to claim 15, wherein the tumblers consist of turnable disks arranged close by each other, the carrier roller being situated radially outside said disks and carrying a plurality of carrier members each adapted to turn one of the tumbler disks to set same in accordance with the corresponding digit of the combination number of the lock and also carrying a carrier member adapted to actuate the bolt to unlock same.

17. A combination lock according to claim 15, wherein a turnable disk is provided to unlock the bolt and wherein the tumblers consist of turnable disks, all said disks being arranged close by each other, the carrier roller being situated radially outside said disks and carrying carrier members of a number equal to the number of the tumbler disks and each adapted, at the oscillatory movement of the setting member to turn one of said tumbler disks to set same in accordance with the corresponding digit of the combination number of the lock, said carrier roller also carrying a carrier member adapted to turn the unlocking disk to unlock the bolt.

18. A combination lock according to claim 15, wherein a turnable disk is provided to unlock the bolt and wherein the tumblers consist of turnable disks, all said disks being arranged close by each other in parallel planes, the carrier roller being situated radially outside said disks and carrying radially projecting teeth of a number equal to the number of tumbler disks plus one, said teeth being each situated in the plane of one of said disks and adapted, at the oscillatory movement of the setting member, to turn one of said tumbler disks in accordance with the corresponding digit of the combination number of the lock and to turn said unlocking disk to unlock the bolt, respectively, said teeth being spaced angularly in relation to each other in such manner that the tooth adapted to turn the unlocking disk follows the teeth adapted to turn the tumbler disks whereby the carrier roller is restored into initial position, when the bolt is unlocked by the unlocking disk.

19. A combination lock according to claim 15, wherein the carrier roller carries radially projecting teeth of a number equal to the number of the tumblers, said teeth being each adapted to actuate one of said tumblers at the oscillatory movement of the setting member, a pawl and ratchet mechanism to turn the carrier roller stepwisely at the oscillatory movement of the setting member so as to bring said teeth consecutively into operative position to engage the corresponding tumbler and to set said tumbler in accordance with the corresponding digit of the combination number of the lock, and means to restore the carrier roller into initial position independently of the angular position of said roller.

20. A combination lock according to claim 15,

wherein means are provided to restore said carrier roller into initial position independently of the angular position of the roller, said means comprising means operable by the setting member to engage the tumbler setting means and the bolt unlocking means at the oscillatory movement of the setting member.

21. A combination lock according to claim 15, wherein a turnable disk is provided to unlock the bolt and wherein the tumblers consist of turnable disks, all said disks being arranged close by each other in parallel planes, the carrier roller being situated radially outside said disks and carrying radially projecting teeth of a number equal to the number of the tumbler disks plus one, said teeth being each situated in the plane of one of said disks and adapted, at the oscillatory movement of the setting member, to turn one of said tumbler disks in accordance with the corresponding digit of the combination number of the lock and to turn said unlocking disk to unlock the bolt, respectively, and wherein means are provided to restore said carrier roller into initial position independently of the angular position of the roller, said means comprising a toothed member adapted to co-operate with the setting member and carrying a plurality of teeth arranged in interspaced planes coinciding with the planes in which the teeth on the roller are arranged and adapted, at the oscillatory movement of the setting member, to be brought into engagement with the teeth of the roller.

22. In a combination lock, an oscillatory setting member, a plurality of tumbler disks and an unlocking disk adapted to control a bolt, all said disks being arranged close by each other and mounted for rotation around an axis coinciding with the axis of oscillation of the setting member, a setting tooth and a restoring tooth on each of said tumbler disks and said unlocking disk, a third tooth on said unlocking disk adapted to engage the bolt, a carrier roller rotatably mounted on the setting member eccentrically in relation to the axis of oscillation thereof and radially outside said disks, a plurality of teeth on said roller projecting radially therefrom in interspaced planes each coinciding with the plane of one of the disks, a pawl and ratchet mechanism operable by the setting member to rotate said carrier roller stepwisely so as to bring the teeth of said roller consecutively into operative position to engage the setting tooth of the corresponding disk, whereby at the oscillatory movement of the setting member the tumbler disks are set in accordance with the combination number of the lock and the unlocking disk is turned so as to cause unlocking of the bolt by the engagement of said third tooth of the unlocking disk, said pawl and ratchet mechanism comprising a turnable toothed member having a tooth adapted to engage all of the teeth of the carrier roller to effect said stepwise movement thereof and a plurality of teeth arranged in interspaced planes coinciding with the planes in which the teeth of the roller are arranged and adapted, at the oscillatory movement of the setting member, to be brought into engagement with the teeth on the roller to restore said roller into initial position independently of the angular position of the roller, and a restoring bar carried by the setting member and adapted to engage the restoring teeth of the disks to restore said disks into initial position at the oscillatory movement of the setting member.

HERNFRID EVALD BERGGREN.
